UNITED STATES PATENT OFFICE.

WILLIAM F. WEISGERBER AND IDA C. HIMMER, OF NEW YORK, N. Y., ASSIGNEES, BY DIRECT AND MESNE ASSIGNMENTS, TO THE STANDARD ELECTRIC CLOCK COMPANY, OF SAME PLACE.

ELECTRIC WINDING DEVICE FOR CLOCKS.

SPECIFICATION forming part of Letters Patent No. 350,177, dated October 5, 1886.

Application filed April 23, 1884. Serial No. 128,842. (No model.)

To all whom it may concern:

Be it known that we, WILLIAM F. WEISGERBER and IDA C. HIMMER, citizens of the United States, residing in New York, in the county and State of New York, have invented certain new and useful Improvements in Electric Winding Devices for Clocks, of which the following is a specification.

Our invention relates to certain improvements in the construction of electric winding mechanism for clocks.

The object of the invention is to provide means for communicating an actuating force to the clock mechanism from an electric battery and to impart the same to the clock-movements through the action of a spring, which is adapted to exert a sufficient tension upon the same to impel the clock during a short period independently of the electric currents from the battery.

The invention consists in constructing the apparatus substantially in the following manner: The pendulum of the clock is equipped with a circuit-closing device adapted to complete the circuit-connections of an electric battery through an electro-magnet at predetermined intervals. The electro-magnet thus periodically vitalized is provided with an armature, which, when it is attracted toward the poles of the electro-magnet, raises a weighted lever, which is employed for winding the spring whereby the clock is actuated. Upon this lever is carried a pawl, which engages the successive teeth of a ratchet-wheel and advances the same step by step during the successive vibrations of the lever. The coil-spring which is employed for communicating the force to the clock mechanism surrounds an arbor, upon which this wheel is mounted, and the two ends of the same are respectively attached to this arbor and to the ratchet-wheel. The spring is so organized that a limited number of revolutions of the wheel may be effected before it is wound to its limit, and the amount of energy thus stored up in the spring is sufficient to actuate the clock for a period dependent upon the train mechanism of the clock. In practice we prefer to actuate the electro-magnet once a minute, and to so construct the parts of the clock that one revolution of the arbor of the ratchet-wheel will drive the clock

for an hour. Since, therefore, the lever is vibrated once each minute it would be necessary that there should be but sixty teeth upon the wheel for the purpose of impelling it at 55 the requisite rapidity for actuating the clock continuously.

Whenever the winding device is constructed to actuate the lever once per minute, it is found in practice that a great advantage is gained by 60 constructing the ratchet-wheel with less than sixty teeth, so that each movement of the armature will advance the same a fraction of a revolution more than its arbor is revolved during the next succeeding interval, and the spring 65 will thus eventually be kept constantly wound. By the excess in winding thus obtained any danger of the stopping of the clock which might arise from a temporary failure on the part of the pawl and ratchet to perform their 70 functions is overcome. After the spring has thus been wound to its full extent the driving-power will be imparted directly to the clock by the weight of the lever. In practice it is found that by constructing the ratchet-wheel 75 with fifty-two teeth it will serve the purpose to the best advantage. The same or similar results may be derived by increasing or by still further diminishing the number of teeth of the ratchet-wheel and increasing or diminishing the frequency of the vibrations of the lever correspondingly.

For the purpose of conveniently giving to the spring the necessary tension when the clock is started, a small rod is applied to the actuating-lever, whereby it may be readily actuated in the proper manner to wind the spring. There is also applied to the armature of the electro-magnet a device for transmitting impulses from an independent battery to a series 90 of secondary electric clocks for the purpose of actuating the same.

In the accompanying drawings, Figure 1 is a front elevation, partly in section, of a clock embodying the features of the invention; and 95 Fig. 2 is a plan view of the same. Fig. 3 illustrates certain details of construction. Fig. 4 is a section on the line 4-4, Fig. 3.

Referring to these figures, A represents the frame of the clock, and B the pendulum-rod, 100 which is actuated by means of an escapement, C. A circuit-closing device, D, of any suitable

ble form is applied to the pendulum-rod B, and is preferably organized to close the circuit of a battery, O, at any predetermined intervals—say once per minute. Included in the circuit thus closed is an electro-magnet, E, which is provided with an armature, F. The armature F is preferably supported from the frame A by means of an adjustable bracket, f, which permits of the movement of the entire armature toward and away from the poles of the magnet.

Upon the armature F is carried an adjustable extension or arm, g, which extends above the short arm of a lever, H. The arm g is preferably rendered adjustable toward and away from the lever H by means of a screw, g', extending through a slot, g'', in the arm, and it is vertically adjustable by means of the screw g'' extending through the arm and pressing against the surface of the armature. The lever H is supported upon a suitable arbor, h', and carries at the extremity of its longer arm a weight, h'', which is preferably made rectangular, as shown in the drawings, and when elevated it is stopped by means of a device, h³, which is technically termed a "piano-key lock." This device consists of a pivoted bracket constructed with two arms, which extend from each other at an angle, and serve to grasp the extremity of the lever and to prevent it from being elevated too great a distance. For the purpose of rendering its movements noiseless the contact-surfaces of the lock and lever are muffled by means of fibrous material h³. An adjustable limiting-stop, v, is applied to the lever H, and this is preferably provided with a contact-cushion, v', of soft material, for the purpose of rendering the striking of the lever against the stop noiseless.

Upon a suitable bracket on the lever H is carried a pawl, i, which is pressed against the periphery of a toothed wheel, J, by means of a spring, i'. The movements of the lever in response to the action of the armature E cause the pawl i to engage the successive teeth upon the ratchet-wheel and to advance the same during the movement of the armature away from the poles of the electro-magnet. A dog, j', is provided for preventing a retrograde movement of the wheel J. The wheel J is loosely mounted upon an arbor, j'', and is connected therewith by means of a spring, j³, preferably inclosed in a drum, j. One end of this spring is attached to the arbor and the remaining end to the ratchet-wheel in such a manner that it will be wound by the movement of the wheel J in response to the action of the pawl i. The spring is preferably of such length that it is capable of permitting several revolutions of the wheel. The tension of the spring when thus wound imparts to the clock mechanism the required force for actuating the same through a toothed wheel, K, which is rigidly mounted upon the arbor j''. The arbor j'' is preferably the arbor upon which the hour-hand of the clock is carried, and therefore completes one revolution an hour.

As in the ordinary clocks and distinguished from the going-barrel movement, the spring j³ runs off from the inside, turning its arbor. In running down, the pin p² is carried around from the position shown in Fig. 3, making three-quarters of a turn until it strikes the pin p'. From the moment of its engagement with this pin it carries the arm P away from its contact with the pin p³, and may carry it a complete turn until it again comes in contact with that pin or on the other side from the position shown in the figure. In winding, if the parts were in the position last named the pin p³ is carried away from the arm P and advanced an entire revolution lacking the width of the arm P, whereupon it engages that arm on its other side, as shown in Fig. 3. It will then carry the arm P forward with it until the pin p' engages the pin p²; but as these were in contact in running down it will take an entire revolution to bring them again in contact. In this manner two entire revolutions of the arbor will be permitted before both ends of the arm P are engaged.

For the purpose of readily giving to the lever H the necessary movements to wind the spring when it is first set up, or when by any chance it has been allowed to run down, a small rod, w, is supported beneath the lever in the brace w' of the frame. This rod is of such length that it extends below the frame, so that it may be easily reached. By pushing the rod upward the lever, and the pawl which is carried thereon, may be actuated in precisely the same manner as is accomplished by the electro-magnet, and the spring will then be wound up.

For the purpose of employing the movements of the armature F to transmit impulses at the proper intervals for actuating one or more secondary electric clocks, there is attached to the armature an extension, R, carrying an adjustable contact-arm, S. The arm S is preferably divided at its extremity, and carries upon each of the two forks thus formed a contact-point, as shown at s' and s''. One of these contact-points, s', extends a greater distance from the armature than the remaining one, s''. Above the contact-points s' and s'' extends a similar contact-arm, T, carrying contact-points t' and t'', respectively, which constitute the remaining electrode of the circuit of an electric battery, o', in which are included secondary clocks, as represented at V.

We claim as our invention—

1. The combination, substantially as hereinbefore set forth, of a revolving arbor, a wheel movable upon said arbor, a revolving arm also carried upon said arbor, and two stops respectively carried upon said arbor and wheel for engaging the respective extremities of said arms.

2. The combination, substantially as hereinbefore set forth, with a spring in a clock-winding mechanism, of a weighted lever for communicating energy to said winding mechanism, an electro-magnet and its armature for placing said weighted lever in position to actu-

ate said winding mechanism, means, substantially such as described, for preventing the further winding of said spring when it is under a predetermined tension, and a rod for manually actuating said lever.

3. The combination, substantially as hereinbefore set forth, of a clock mechanism, an electro-magnet periodically vitalized through the action of said mechanism, a spring or weight for actuating said mechanism, a lever actuated by said electro-magnet, a ratchet-wheel advanced by the action of said lever, and having a number of teeth less than the number of times said lever is actuated during a single revolution of the arbor primarily actuated by said wheel, and a rod for manually actuating said lever.

4. The combination, substantially as hereinbefore set forth, with a clock-escapement, of a spring for actuating said escapement, of a ratchet-wheel and pawl for winding said spring, a lever carrying said pawl, an electro-magnet, its armature and armature-lever for actuating said lever, an extension carried upon said armature-lever, an adjustable insulated

circuit-closing arm carried upon said extension, a contact-point applied thereto, and an electric circuit having its terminals at said point and circuit-closing arm, respectively.

5. The combination, substantially as hereinbefore set forth, with a clock-movement and an electrical winding device applied thereto, consisting of an electro-magnet and armature-lever, a ratchet-wheel and intermediate mechanism for revolving said ratchet-wheel by the movements of said armature-lever, of a circuit-closing arm carried by said armature-lever, having a forked end, one fork being lower than the other, and two electrically-connected contact-points respectively applied to these forks.

In testimony whereof we have hereunto subscribed our names this 21st day of April, A. D. 1884.

WILLIAM F. WEISGERBER.
